UNITED STATES PATENT OFFICE.

MILES ROLFE, OF VANANDA, MONTANA.

CLOTHES BOILER.

Application filed October 10, 1921. Serial No. 506,747.

To all whom it may concern:

Be it known that I, MILES ROLFE, a citizen of the United States, residing at Vananda, in the county of Rosebud and State of Montana, have invented new and useful Improvements in Clothes Boilers, of which the following is a specification.

This invention relates to improvements in clothes boilers and has for an object the provision of a boiler in which articles of clothing may be boiled in separate compartments.

Another object of the invention is the provision of means for conveniently removing the clothes from the boiler and for draining the surplus water therefrom, prior to their removal, the said means including a cage-like structure of novel formation, which may be supported in elevated or draining position.

Another object of the invention is the provision of means for strengthening the boiler and for spacing the latter above the top of the stove, so as to protect the boiler from wear, due to scraping or other contact.

With the above and other objects in view, the invention further includes the following novel features and details of construction, to be hereinafter more fully described, illustrated in the accompanying drawings and pointed out in the appended claim.

In the drawings:—

Figure 1 is a top plan view of a boiler with the invention applied thereto.

Figure 2 is a longitudinal sectional view of the same showing one container elevated.

Figure 3 is a bottom plan view.

Figure 4 is a section on the line 4—4 of Figure 1.

Figure 5 is a detail perspective view of one of the containers.

Referring in detail to the drawings, wherein like characters of reference denote corresponding parts, the reference character 10 indicates a boiler of the usual or any preferred shape or construction. This boiler is provided with a centrally arranged transverse partition 11, which divides the boiler into separate compartments 12.

The bottom of the boiler is surrounded by a flange 13 which extends downwardly from the bottom edge and which is connected by a centrally located, longitudinally disposed flange 14. This provides a support for the

boiler and spaces the bottom thereof above the top of the stove so as to prevent contact and reduce wear upon the bottom.

Each of the compartments 12 is preferably provided with a draw off cock 15, by means of which the boiler may be emptied without lifting the said boiler and its contents.

One of the novel features of the invention resides in the provision of means for removing articles from within the boiler and for drawing the surplus water from these articles prior to their removal. To this end, the invention includes a container 16, one of which is removably located in each of the compartments 12, being slightly less in both length and width than the said compartments so as to permit of a limited movement therein. These containers are each formed of a frame 17 which is shaped to fit the bottom of the compartment and which has secured thereto longitudinally disposed spaced slats 18, which provide a bottom. One of these slats, preferably the center slat has its opposite ends extending upwardly to provide handles 19 and these handles terminate in loop-like grips 20. The grips 20 are formed by bending the extremities of the handles inwardly on a horizontal line and downwardly toward the handle, to which the said extremity is fastened. This forms a convenient means for grasping the containers and lifting them from the compartments 12. In addition, there is extended upwardly from the bottom of the container, or from the frame 17, spaced standards 21 and these standards and the handles 19 are connected by horizontally arranged spaced strips 22 so that a cage-like structure is formed whose shape corresponds to the shape of the compartment 12.

One of the handles 19 is provided with an outwardly extending headed stud 23 for engagement over the upper edge of the partition 11, while the other handle 19 has secured upon its inner face a spring arm 24 whose extremity is provided with an angularly extending portion 25. This portion 25 operates within an opening or slot 26 provided in the said handle 19 and forms a yieldingly movable latch or lug which is adapted to engage over the upper edge of the boiler.

In the use of the invention, the articles of clothing are placed in the containers and the latter are inserted within the compartments and a lid placed thereon. After a sufficient lapse of time, the clothes may be removed and to do this, the handles are grasped by the grips 20 and the container elevated. After the container reaches the proper height, the said grips 20 may be engaged over the upper edge of the partition 11 and the latch or lug 25 will spring into engagement over the upper edge of the boiler, as clearly shown in the drawings.

The invention is susceptible of various changes in its form, proportions and minor details of construction and the right is herein reserved to make such changes as properly fall within the scope of the appended claim.

Having described the invention what is claimed is:—

A clothes boiler of the class described comprising a partition dividing said boiler into compartments, drainers in said compartments respectively, handles on said drainers, a headed stud on one of said handles extending outwardly therefrom, a spring latch on the remaining handle normally in contact with the inner wall of the compartment when the drainer is in lowered position and adapted to spring outwardly when the drainer is withdrawn from the compartment to cooperate with said stud and engage the top of the compartment to hold the drainer in draining position.

In testimony whereof I affix my signature.

MILES ROLFE.
